PHINEAS M. CADWELL, OF MALVERN, IOWA, ASSIGNOR TO CADWELL & SALYERS, OF MALVERN, IOWA, A COPARTNERSHIP COMPOSED OF PHINEAS M. CADWELL AND WILLIAM H. SALYERS.

ROAD-GRADING APPARATUS.

1,355,938.

Specification of Letters Patent. Patented Oct. 19, 1920.

Application filed February 2, 1920. Serial No. 355,862.

To all whom it may concern:

Be it known that I, PHINEAS M. CADWELL, a citizen of the United States, residing at Malvern, in the county of Mills and State of Iowa, have invented certain new and useful Improvements in Road-Grading Apparatus, of which the following is a specification.

The invention relates to grading apparatus adapted for use in excavating and 10 more particularly in building roads, where it becomes necessary to cut off hills, fill in gullies and the like; and the general object of the invention is to provide an apparatus of a practical character by means of 15 which the cost of labor and construction generally may be reduced to a minimum.

More specifically, one of the objects of 20 the invention is to provide an apparatus of the character indicated which combines the features of simplicity, power, and low cost 25 of manufacture.

A serious difficulty which has rendered former devices of this general character impractical is the great tendency of the cable 30 employed in hauling the scoops, to become worn by reason of its frictional contact with the winding drum. An important object of the present invention is to provide an improved cable actuating mechanism consisting 35 of a plurality of sheaves adapted to overcome to a maximum degree the objection referred to.

A further object of the invention is to 35 provide improved means for positioning the portions or strands of the cable traveling in opposite directions and carrying the loaded and empty scoops respectively, relative to each other and to the work in the grading operation.

40 The objects of the invention thus generally stated together with other and ancillary advantages are attained by the construction and arrangement illustrated in the accompanying drawings wherein I have illustrated one embodiment of the invention. I 45 desire to have it understood that although the invention is illustrated and hereinafter described with considerable particularity, it is not intended to be limited to the precise construction and arrangement shown since 50 various other embodiments of the invention may be constructed without departing from the spirit and scope thereof.

In the drawings Figure 1 is a fragmentary

top plan view of the apparatus. Fig. 1^a is 55 a detail view showing on an enlarged scale the arrangement of the winding sheaves to minimize wear upon the cable. Fig. 2 is a side elevation of the actuating mechanism for the cable. Fig. 3 is a side elevation of 60 one of the means for positioning the oppositely traveling strands of the cable relative to each other. Figs. 4 and 5 are detail views of one of the winding sheaves of the cable actuating mechanism. Fig. 6 is a detail view of the clamp by means of which the scoops are detachably connected to the cable. 65

The apparatus comprises generally an endless cable 7, actuating mechanism 8 for 70 the cable, an anchoring device 9 for the cable at the end of the apparatus opposite the actuating mechanism, and a series of scoops 10 arranged to be detachably connected to the cable. 11 designates generally a frame 75 (Fig. 3) by means of which the oppositely traveling strands of the cable are positioned relative to each other at one end of the apparatus, while 12 indicates guiding means for relatively positioning the strands of the 80 cable at the opposite end of the apparatus.

The cable 7 may be of any preferred character, being preferably made of wire; and is of the endless type forming strands 7^a and 7^b traveling in opposite directions. 85 The strand 7^a is herein designated the draft cable and the strand 7^b the return cable.

The actuating mechanism 8 comprises two sets of sheaves 13, said sets being mounted respectively on shafts 14 and 14^a journaled 90 in a frame 15. The shafts 14 and 14^a also have fixed thereon spur gears 16 near their opposite ends which mesh with pinions 17 fixed upon a drive shaft 18 also journaled in the frame. The drive shaft carries at its 95 free end a pulley 19 adapted to be actuated from any suitable source of power. Herein, the shaft 14 has fixed thereon two sheaves 13 which constitute one set, and the shaft 14^a carries three sheaves 13 which constitute 100 another set. The sheaves on each of said shafts are spaced apart and relatively arranged so that the cable 7 runs first to a sheave of the rear set, thence to a sheave of the forward set, and back and forth between the sets until it finally passes from a sheave of the rear set away from the actuating mechanism. The peripheral groove of each

of the sheaves is preferably V-shaped in form, and the sheaves of the respective sets are relatively arranged so that the walls thereof which are engaged by the cable in 5 running from a sheave of one set to a sheave of the other are substantially in alinement. By this arrangement the cable is prevented from riding upon the rims of the grooves to any appreciable extent.

- 10 In order to insure against slippage of the cable, each of the sheaves is provided at the bottom of its V-groove with a groove 20, of a width less than the thickness of the cable, so as to cause the cable to engage with the 15 sheave with a wedging action.

For guiding the opposite strands of the cable as they enter and leave the actuating mechanism, a pair of guiding means 21 and 22 are provided on the machine frame 15.

- 20 The guiding means 21 comprises two horizontal pulleys mounted in a bracket 23 in spaced relation, and a pulley 24 mounted on a horizontal axis, substantially midway between the axes of the horizontal pulleys. 25 The guiding means 22 comprises a single pulley mounted on a vertical axis in a bracket 25. Said guiding means are respectively arranged to guide the draft cable 7^a to the under side of the first sheave of the 30 rear set and from the upper side of the last sheave of the rear set.

The anchoring device 9 for the cable at the end of the apparatus opposite the actuating mechanism 8 may be of any suitable 35 or preferred character. Herein, it is shown as consisting of a platform 26 arranged to be anchored in a suitable way to the ground, as by means of devices 27, and having mounted thereon a sheave 28 between the 40 platform and a spider 29 fixed thereon.

The scoops 10 may be of any preferred type and are detachably secured to the cable 7 as by means of the device shown in Fig. 6. Said device consists of a block 30 having 45 pivoted thereon a cam lever 31 adapted to coöperate with a jaw 32 on the block, the parts being so arranged that a pull of the cable upon the scoop tends to tighten the clamp on the cable. It will be seen that 50 while the clamp is arranged to effectively secure the scoops to the cable, they are at the same time capable of easy detachment.

The means for relatively positioning the opposite strands of the cable at the end of the apparatus adjacent the actuating mechanism may be of any suitable or preferred construction. Herein, by way of example, I have shown a frame 33 suitably supported in upright position as by means of guy ropes 55 34 and comprising a pair of parallel bars 33^a and 33^b located one above the other and having a plurality of apertures 35 for receiving vertical supporting rods 36 for guide pulleys 37. By this arrangement, the space 60 65 between the opposite strands of the cable

may be readily varied as may be desired. Moreover, it will be observed that the guide pulleys 37 are free to move vertically on their supporting rods within the limits defined by the bars 33^a and 33^b so as to accommodate the cable to the various degrees of elevation in the road being graded.

The guiding means 12 for the cable at the end of the apparatus opposite the guiding means 11 are provided for the purpose of varying the positions of the cables in accordance with the progress of the work without necessitating the movement of the anchoring device 9. This guiding means 12 may also be of any preferred type being herein shown 75 80 as consisting of a pair of pulleys 38 mounted on pivots 39 mounted in arms 40 which are suitably anchored to the ground.

It will be understood that the apparatus may be of any preferred size, but I have 85 found in practice that it is possible to extend it over a long expanse of territory to be graded, and of course, as many scoops may be employed as may seem desirable. After the apparatus has been located, the 90 scoops are manipulated by one or more men at the desired point, so that they will become filled, and are then carried by the draft cable to the point where they are to be dumped. After the scoop is dumped the 95 attendant detaches it from the power cable and drags it over to the return cable, attaching it thereto for carriage to the point of filling. It will be seen that by the guiding means 11 and 12 the cables may be readily 100 positioned so as to minimize the work of handling the scoops as well as to properly position the cables with reference to the point or points to be graded.

I have also found in practice that with 105 the use of winding mechanism of types other than that which I employ herein, such, for example, as winding drums, the wear on the cable is so great as to render the apparatus wholly impractical, whereas my improved construction and arrangement for the cable gripping means of the actuating mechanism permits of the operation of the apparatus for a substantially indefinite length of time without showing appreciable 110 wear upon the cable.

It will thus be apparent that I have produced a road grading apparatus of a very practical character, which is relatively simple in construction, which may be operated 120 with a minimum expenditure of effort and labor on the part of the attendants, and which is of maximum durability.

I claim as my invention:

1. A road grading apparatus comprising, 125 in combination, an endless cable, cable actuating mechanism at one end of the apparatus, an anchoring device for the cable at the other end of the apparatus, a plurality of scoops adapted to be detachably con- 130

5 nected to the cable, and an upright frame having a pair of guide pulleys for the opposite strands of the cable, said pulleys being mounted in the frame so as to be laterally adjustable to vary the positions of the cable strands as the work progresses.

2. A grading and excavating apparatus comprising, in combination, a frame, a pair of shafts mounted in parallel relation on 10 said frame and spaced a substantial distance apart, a drive shaft also mounted on the frame intermediate said pair of shafts and having a gearing connection with both of said pair of shafts, an endless cable, a plurality of cable-gripping sheaves on each of said pair of shafts arranged so that the cable passes successively from a sheave on one shaft to a sheave on the other shaft with the incoming and outgoing strands of the 20 cable traveling in opposite directions with reference to each other and in substantially parallel relation, an anchoring sheave for the cable adapted to be fixed at a point removed from the frame, and a plurality of 25 scoops having means whereby they may be detachably secured to the oppositely traveling strands of the cable.

3. In a grading apparatus, the combination with an endless cable, of actuating 30 mechanism therefor comprising a pair of parallel shafts carrying respectively a forward and a rear set of sheaves, each set comprising a plurality of sheaves having substantially V-shaped grooves arranged to 35 grip and guide the cable from one set to the other in succession, and the sheaves of one set being arranged in vertical planes substantially midway between pairs of sheaves of the opposite set.

40 4. In an apparatus of the character described, the combination with an endless cable, of actuating means therefor comprising a pair of horizontal substantially parallel shafts carrying respectively two sets of 45 sheaves, and means for rotating said sheaves, the sheaves of each set being spaced apart and positioned with reference to the sheaves of the opposite set so as to permit of the substantially unrestricted movement of the 50 cable successively from one set to the other, there being a greater number of sheaves in one set than in the other.

5. A grading and excavating apparatus comprising, in combination, a frame, a pair 55 of shafts mounted in parallel relation on said frame and spaced a substantial distance apart, means for driving at least one of said shafts, an endless cable, a plurality of cable-gripping sheaves on each of said 60 shafts arranged so that the cable passes successively from a sheave on one shaft to a sheave on the other shaft with the incoming and outgoing strands of the cable traveling in opposite directions with reference to each

other and in substantially parallel relation, 65 an anchoring sheave for the cable adapted to be fixed at a point removed from the frame, and one or more scoops having means whereby they may be detachably secured to either the incoming or outgoing strands of 70 the cable.

6. A grading and excavating apparatus comprising, in combination, a frame, a pair of shafts mounted in spaced parallel relation on said frame, means for driving at 75 least one of said shafts, an endless cable, a plurality of cable-gripping sheaves on each of said shafts arranged so that the cable passes successively from a sheave on one shaft to a sheave on the other shaft with 80 the incoming and outgoing strands of the cable traveling in opposite directions with reference to each other and in substantially parallel relation, an anchoring sheave for the cable adapted to be fixed at a point re- 85 moved from the frame, and one or more scoops having means whereby they may be detachably secured to either the incoming or outgoing strands of the cable, said frame having mounted thereon a pair of pulleys 90 operable to guide the strands of the cable passing to and from the actuating sheaves.

7. An excavating apparatus comprising, in combination, a frame, a pair of shafts mounted in parallel relation upon said frame, a drive shaft also mounted on the frame and having a gearing connection with each of said pair of shafts, an endless cable, a plurality of cable-gripping sheaves mounted on said pair of shafts and arranged to 100 successively receive and guide the cable with the incoming and outgoing strands thereof traveling oppositely, guide pulleys mounted on the frame at one end thereof whereby to maintain the incoming and outgoing strands 105 of the cable substantially parallel, an anchoring device adapted to be secured a spaced distance from the frame, and means between the frame and the anchoring device for positioning the cable with reference to 110 the work.

8. An apparatus of the character described comprising, in combination, a draft cable and a return cable, actuating mechanism for the cables, an anchoring device for 115 the cables at the end of the apparatus opposite said actuating mechanism, a pair of guide pulleys adjacent said anchoring device for positioning the strands of the cable relative to each other and with reference 120 to the work, and means for guiding the cables into and from the actuating mechanism including a pair of guide pulleys mounted for movement longitudinally upon upright axes.

In testimony whereof I have hereunto set my hand.

PHINEAS M. CADWELL.
